SPECIFICATION forming part of Design No. 15,602, dated December 9, 1884.

Application filed October 2, 1884. Term of patent 7 years.

To all whom it may concern:

Be it known that I, ANDREW LITTLE, of the city, county, and State of New York, have invented and produced a new and original Design for a Font of Printing-Type, of which the following is a specification.

The nature of my design is clearly shown in the accompanying typographic impression, to which reference is made; and it consists of 10 an ornamental letter provided with the light scroll ornaments, except in the case of the letters H, I, M, N, U, X, and Y, shaded upon the right and below by a series of short light

horizontal lines following the configuration of the letter.

The character of the design is preserved in the symbol "and," the dollar-mark, the numerals, and the punctuation-marks.

Having now described my invention, I claim as new—
